C. E. HAWXHURST

FOLDING PAPER DEVICE, INCLUDING ITS CONSTITUENT BLANK

Filed April 6, 1923

Fig. 2.

INVENTOR
CHARLES E. HAWXHURST

BY *Walter S. Edmunds*

ATTORNEY

UNITED STATES PATENT OFFICE.

CHARLES EDWARD HAWXHURST, OF NEW HAVEN, CONNECTICUT, ASSIGNOR TO NATIONAL FOLDING BOX COMPANY, OF NEW HAVEN, CONNECTICUT, A CORPORATION OF NEW JERSEY.

FOLDING PAPER DEVICE, INCLUDING ITS CONSTITUENT BLANK.

Application filed April 6, 1923. Serial No. 630,213.

To all whom it may concern:

Be it known that I, CHARLES E. HAWXHURST, a citizen of the United States, and a resident of the city of New Haven, county 5 of New Haven, and State of Connecticut, have invented a certain new and useful Folding Paper Device, Including its Constituent Blank, of which the following is a specification.

10 My present invention relates to essentially tubular devices of ovaloid cross-section suitable for use as containers, or otherwise, and composed of a unitary sheet of paper, or similarly bendable material, and of such 15 form and construction as to be storable or shippable in their flat, i. e. in "knocked-down" form, and, when required, "set up" for use.

Hitherto commercially and practicably 20 utilizable unitary tubular types of such devices, set-up without adhesive or other fasteners, have, I believe, been of rectangular, or polygonal, cross-section transverse their central longitudinal axes, their exteriors correspondingly presenting lateral angular 25 projections or relatively sharp corners.

It has become desirable that such containers be made of size and shape such as to carry conveniently in the user's pocket, for 30 example, small articles such as medical tablets, cigarettes, etc., in which case their referred to angularities are more or less objectionable not only mechanically but also as unconforming with conventional standards requiring mostly unangular, i. e. curved or rounded exteriors as for example in present cigarette packages or cases.

The objects of my present invention comprise provision of a readily and economically 40 made blank of such form and construction as to satisfy the referred to requirements and as to be firmly and accurately set up for use and thereafter easily manipulated without exercise of any special skill.

45 I attain these objects by the type of blank productive of a container such as illustrated in the accompanying drawings in which—

Figure 1 is a view of the blank;

50 Figure 2 is a perspective of the container set up from the blank of Figure 1;

Figure 3 is a cross-sectional view taken on the line 3—3 of Figure 2.

Similar numerals refer to similar parts throughout the several views.

My unitary blank, as shown in Figure 1, 55 comprises an essentially parallelogrammatic, or rectangular, tubular, body-composing, part, or section, 4, which being, as shown, untraversed by any creased, scored, or otherwise weakened bend lines in the material is readily uprollable into a variously curved unangular conformation in which, when secured as hereafter described, it serves as the laterally enclosing sides of the tubular body 60 of the container.

The blank also comprises a plurality of flap members 6, 6', 7, 7', 8, 8', 9, 9', which, in the knocked down position outwardly project from said body section and which, on setting up the blank, are inwardly bent relatively to said body along intermediately disposed, hereafter described creased, or scored, "bend" lines in the material. These flaps, as hereafter described, constitute means essentially carried by the body member 65 4 to, on setting up of the device, close the open ends of the tube and also contribute to maintenance of its sides in their desired outwardly circular or bulging form.

Relatively, straight scored, or creased 70 bend lines 10, 10', are made in the material intermediate the body section 4 and the flaps 7, 7', and on which the latter are bendable as aforesaid.

Similar bend lines 11, 11', are, for a similar 75 purpose, similarly located intermediate said body section 4 and the flaps 9, 9'.

In the bend lines 11, 11', are slots 12, 12' cut through the material.

The flaps 7, 7' comprise tongues 5, 5', cooperative with the slots 12, 12' and bendable on creased or scored lines 13, 13'.

Inwardly circular scored or creased bend lines 14, 14' are made in the material intermediate the body section 4 and the flaps 8, 8'. 85 The body section 4 comprises a part thereof 4^a, the side edges of which are cut inwardly curved as shown in Figure 1.

A slot 15 is cut through the material intermediate the main body section 4 and the 90 said part thereof 4^a. The body section 4 also comprises a part thereof, 4^b carrying a tongue 16 cooperative with the slot 15.

Inwardly circular scored or creased bend

lines 14^a, 14^b, are made in the material intermediate the part 4^b of the body section 4 and the flaps 6, 6'.

The blank is set up for use as a container, 5 or otherwise, in the following manner.

The body 4, devoid of therein bend lines, is, as it were, bent or rolled into the tubular ovaloid form above referred to until its parts 4^a, 4^b, are brought into mutually overlapping 10 extended contact with each other and the tongue 16 is then inserted into the slot 15 to maintain the body portion thus brought into approximately its said formation. The flaps 6, 6', 8, 8' are then turned in on the 15 curved bend lines 14^a, 14^b, 14, 14', respectively, thereby imparting corresponding outwardly curved contours to the sides 4, 4^b. The flaps 9, 9' are turned in on the respective bend lines 11, 11' until about rectangular to the central axis of the semi-cylindrical body section 4, the flaps 7, 7', similarly turned in on the respective bend lines 10, 10' and the tongues 5, 5', inserted in their cooperative slots 12, 12', or, if preferred the 25 flaps 9, 9' may be turned in in advance of the flaps 6, 6', 8, 8'.

The inwardly circular bend lines cooperate with the inwardly circular side edges of the part 4^a of the body 4 to cause and maintain 30 the curvatures of the material required to impart the desired partially rounded or circular conformation of the exterior of my device or container.

Having now described my invention, what 35 I claim as new and desire to secure by Letters Patent is the following, viz:

1. A parallelogrammatic foldable container formed from a single piece of material comprising a flat body portion having two 40 rectangular, oppositely-disposed, outwardly circular sides held in correspondingly circular bent lines at each of the four corners when the container is set up.

2. A parallelogrammatic foldable container formed from a single piece of material comprising a body portion having flat top and bottom members, two rectangular, oppositely disposed, outwardly circular sides, and inturned end flaps of the same width as the 50 depth of the container bendable on circular lines to hold said sides at both ends in said circular position.

3. A parallelogrammatic foldable container formed from a single piece of material 55 detachably secured in ovaloid form with top and bottom flat and mutually parallel, and having two rectangular, oppositely dis-

posed, outwardly circular sides maintained in correspondingly circular bent lines at each of the four corners when the container 60 is set up.

4. A parallelogrammatic foldable container formed from a single piece of material comprising a body portion detachably held in tubular form having both top and bottom flat and having two rectangular, oppositely disposed, outwardly circular sides, and inturned end flaps of the same width as the depth of the container bendable at right angles on circular lines to hold said sides in curved position at each of the four corners. 70

5. A unitary paper blank for a foldable container comprising a body portion detachably held in tubular ovaloid form in cross-section with flat rectangular top and bottom members, outwardly circular sides integral with both top and bottom, inturned end flaps of the same width as the depth of the container bendable on circular lines from the sides to maintain the latter in position at 76 the four corners, and integral flaps projecting outwardly from the top and bottom at both ends and folded over said inturned end flaps and secured to the body to hold the blank in set-up position. 80

6. A unitary paper blank for a foldable container comprising a body portion detachably held in tubular ovaloid form in cross-section with flat rectangular top and bottom members, oppositely-disposed, outwardly circular sides integral with both top and bottom, inturned end flaps of the same width as the depth of the container bendable on circular lines from the sides to maintain the latter in position at the four corners, and integral flaps projecting outwardly from the top and bottom at both ends and folded over said inturned end flaps and secured to the body to hold the blank in set-up position. 85

7. A unitary paper blank for a foldable container comprising a body portion detachably held in tubular ovaloid form in cross-section with flat rectangular top and bottom members, outwardly circular sides integral with both top and bottom, end flaps having substantially the same width as the depth of the container to maintain the latter in position at the four corners bendable on circular lines from the sides, and integral flaps projecting outwardly from the top and bottom at both ends and folded over said inturned end flaps and secured to the body to hold the blank in set-up position. 100
